(57) **CLAIM**

The ornamental design for a display screen with user interface, as shown and described.

DESCRIPTION

The FIGURE is a front view showing a display screen with user interface according to our new design.

The broken line showing of the remainder of the text message content area and "TEXT" illustrate portions of the user interface which form no part of the claimed design. The broken line showing of a portion of the display screen illustrates the environment of the claimed design and forms no part thereof. The broken line square in the Figure illustrates the boundary of the claimed design, and the square and the area therewith, with the exception of the portion of the paper clip that extends inside the broken line square, form no part of the claimed design.
